UNITED STATES PATENT OFFICE

152,443

DESIGN FOR A FONT OF TYPE

John Randall Walker, Flushing, N. Y., assignor to Norcross, Inc., New York, N. Y., a corporation of New York

Application May 24, 1948, Serial No. 146,557

Term of patent 7 years

(Cl. D64—12)

To all whom it may concern:

Be it known that I, John Randall Walker, a citizen of the United States, residing in the city of Flushing, in the county of Queens and State of New York, have invented a new, original, and ornamental Design for a Font of Type, of which the following is a specification, reference being made to the accompanying drawing, forming part thereof.

I claim:
The ornamental design for a font of type, as shown.

JOHN RANDALL WALKER.
